UNITED STATES PATENT OFFICE

GEORGE A. TAYLOR, OF HYDE PARK, MASSACHUSETTS

STARTING DEVICE FOR INTERNAL COMBUSTION ENGINES

Application filed January 24, 1929. Serial No. 334,656.

This invention relates to starting devices for internal combustion engines and with regard to certain more specific features thereof to automatically engageable and disengagable 5 transmission mechanism governed by the action of an electric motor and by the action of the engine.

Heretofore transmission devices have been used involving a threaded armature shaft 10 extension, or a threaded sleeve on such an extension, for causing axial movement of the pinion into engagement with a ring gear on the fly wheel of an engine. Usually in such devices a spring has been included directly 15 in the drive for the purpose of relieving the shock of backfiring, neutralizing the action of the irregular movement of the engine as the cylinders pass over compression points and minimizing the deleterious effects of end- 20 butting of the pinion teeth with the teeth of the ring gear. To some extent, this arrangement of a spring in the driving connection has served its purpose along the directions 25 indicated but not in a highly satisfactory manner and always with the objection that the springs become distorted and broken, rendering the device inoperative. Another objection has been in the decided shock of 30 impact in such prior devices when the pinion is automatically engaged with the fly wheel gear. These objections have been recognized for many years and many attempts have been made to devise engine starter transmissions 35 which would avoid some or all of these objectionable features.

The present invention has for one of its objects to provide an extremely compact and durable starter drive transmission which shall be highly efficient in operation; one in 40 which the shock of engaging impact is reduced to a minimum; one in which the irregular action of the engine in the starting operation is compensated for at an intermediate point in the drive so that the engine gear and starter pinion have no relative axial movement during the power transmitting 45 operation; one in which the mechanism is protected against any injurious effects of backfiring of the engine during the starting 50 operation and one in which no substantial

torque is transmitted in the starting operation through any of the springs involved.

The invention has for another of its objects to provide a device of the character above described which shall be extremely 55 simple insofar as the number and size of parts employed are concerned and which shall be constructed at very low cost.

The invention accordingly consists in the various features of construction, combinations of elements and arrangements of parts exemplified by the description hereinafter set forth and the scope of the application of which is indicated in the appended claims. 60

In the drawings, 65
Figure 1 is a general assembly plan view showing the starter drive attached in operative position to an internal combustion engine.

Figure 2 is a longitudinal sectional view of 70 the improved starter drive in normally disengaged position.

Figure 3 is a view similar to Figure 2 showing the parts in the positions assumed when 75 the transmission is complete.

Figure 4 is a view similar to Figure 3 showing the action of the parts occurring under the periodic increased speed on the engine fly wheel as the engine passes over compression 80 points or this figure may be taken to indicate the preliminary action of the parts in disengagement of the transmission.

Figure 5 is a view in longitudinal section of a modified form of invention showing the application of a multiple disk clutch in place 85 of the cone clutch shown in Figures 2, 3 and 4.

Figure 6 is a view in longitudinal section of another modified form of the invention showing the application of a separate 90 threaded sleeve to the armature shaft extension of the electric motor instead of cutting the threads directly on this extension as in Figures 2 to 5 inclusive.

Figure 7 is an end view of the starter 95 shown in Figures 2, 3 and 4.

Figure 8 is a sectional view taken on the line 8—8 of Figure 2.

Figure 9 is a sectional view taken on the line 9—9 of Figure 5. 100

Figure 10 is a view of the large spring employed in the starter shown in Figure 6 which may be taken as generally typical of the large springs employed in the mechanisms shown in Figures 2 to 5 inclusive.

Figure 11 is a fragmentary view in plan of the stop pin and collar mechanism shown in Figure 6.

Referring now more particularly to the drawings, Figures 1 to 4 and 7 and 8 thereof, an electric motor is indicated at 20 having an armature shaft extension 21 with a reduced end portion 22, which is threaded as indicated at 23. Surrounding the armature shaft extension 21 is a loose stop washer 22 adapted to bear against a shoulder 23. A sleeve 24 surrounds said armature shaft extension and has a bearing thereon as indicated at 25. This sleeve has a forward bore 26 and a rearward bore 27. A light coiled spring 28 surrounds the armature shaft extension 21 and has its forward end bearing against the stop washer 22 and its rearward end bearing against a shoulder 29 at the end of the bore 26. Arranged within the bore 27 of the sleeve 24 is a heavy compression spring 30 surrounding the threaded portion of the armature shaft extension and arranged between a shoulder 31, at the inner end of the bore, and an exterior cone clutch member 32 splined as at 33 on the sleeve 24. By reason of the spline, the exterior cone clutch member 32 is adapted for relative axial movement with the sleeve 24, but is locked rotatively therewith. This clutch member has a conical friction clutch surface 34 adapted to engage with a friction clutch surface 35 of an internal cone clutch member 36 interiorly threaded as at 37 and engaged with the threads 23 cut on the armature shaft extension. A stop collar 40 is secured to the end of the armature shaft extension and has a forwardly extending stop pin 41 against which the inner clutch member 36 is adapted to strike in its outward movement, thereby preventing the end of said clutch member from jamming against the forward face of the stop collar. A pinion 42 is formed on the forward end of the sleeve.

In the normal disengaged position of the parts, the compression spring 30 is under no appreciable tension. The light spring 28 pressing against the sleeve 24 and reacting against the stop washer 22 is under slight tension normally and urges the sleeve rearwardly creating a definite frictional engagement of the two parts of the cone clutch, so that upon energization of the motor, the armature shaft rotates within the sleeve and its associated clutch, and the threads 23 cause a forward or axial movement of the assembled parts. No appreciable compression of the spring 30 takes place until axial movement of the assembly is resisted as by end butting of the teeth of the pinion with the

teeth 50 of the gear 51 on the fly wheel of the engine, or, as by resistances of the stop washer 22 to the axial movement of the sleeve as shown clearly in Figure 3 of the drawings. When the axial movement is resisted as in either of the foregoing cases, continued rotation of the armature shaft causes continued axial movement of the inner clutch member by reason of the threaded engagement, carrying with it the outer clutch member 32 and compressing the spring 30.

In the event of end-butting of the teeth of the pinion and fly wheel gear, the compression of the spring 30 is slight but sufficient to increase the degree of frictional engagement between the clutch members, thereby causing the sleeve to rotate with the driving shaft. Slight rotation will be enough to carry the teeth into proper meshing position, whereupon the spring 30 immediately expands to its normal position and the axial movement of the sleeve is carried on until the end of the sleeve abuts the stop washer 22. Figure 4 might be taken as illustrative of this last condition and it will be apparent that the spring 30 is again compressed increasing the degree of friction between the clutch members from minimum to maximum. The axial movement of the clutch members is continued until the forward end of the inner clutch member 36 abuts a shoulder 36a on the driving shaft at which time rotative movement is transmitted from the driving shaft through the clutch to overcome the resistance of the engine under all ordinary conditions. To this end I use a relatively heavy spring as shown in Figure 10 of the drawings of approximately $\frac{1}{16}$ " diameter spring steel wire.

As the engine varies in rotative speed going over compression points, a condition known as "bobbing" takes place in many starters of present day designs and sometimes results in complete demeshing and remeshing of the pinion with the ring gear. The present invention avoids any possible demeshing by reason of the fact that the clutch device assumes the reaction to the engine speed variations. No visible axial movement of the pinion or sleeve takes place in the present construction, but the engine variations are reflected in a visible axial reciprocation of the clutch. It will be obvious that when the fly wheel rotates faster than the speed imparted by the motor, a condition which takes place when the engine passes over a compression point, there will be a tendency of the inner clutch member 36 to move axially rearward due to its threaded engagement with the armature shaft extension. The outer clutch member 32 is caused to follow closely by the expansion of the spring 30. As the engine again slows up as by approaching another compression point, the clutch member 36 is again advanced carrying with it

the outer clutch member 32 and recompressing the spring 30. All this takes place without any visible movement of the sleeve away from the stop washer 22.

- 5 If during the starting operation the engine backfires, the inner and outer clutch members slip and to this end the spring 30 is designed to allow such slippage. However, inasmuch as the spring 30 is not directly or 70
10 positively connected to any of the parts and is not in a true sense in the driving chain, there is no possibility of distortion of, or injury to, the spring by reason of such backfiring. 75
15 When the engine commences to operate under its own power, the rotation of the ring gear 51 is much faster than the rotation of the pinion 42 under the influence of the electric motor with the result that the inner 80
20 clutch member is moved axially rearward under the influence of the threads 23. This is effected by reason of the continued frictional engagement of the clutch parts due to the pressure of the spring 30 which first expands 85
25 to its normal length after which the light spring 28 expands causing the sleeve to follow and resume its normal unengaged position shown in Figure 2. 90

In the modification shown in Figures 5 95
30 and 9 of the drawings, a multiple disk clutch is substituted for the cone clutch shown in Figures 2, 3 and 4. The alternate plates or disks in the outer clutch member are indicated at 60 splined to the sleeve as shown in Figure 9 of the drawings and the inner plates or disks 61 are shown as splined to a nut or inner clutch member 62 which has a threaded engagement with the armature shaft extension in the same manner as the inner clutch 100
40 member 36 of the preferred form of the invention.

In the modification shown in Figure 6 of the drawings, instead of cutting the threads directly on the armature shaft extension, an 105
45 intermediate sleeve 65 having threads 66 formed thereon is arranged over an armature shaft extension 67. The sleeve is secured both rotatively and axially to the shaft by a screw 68, which also secures the end collar 69 to the end of the armature shaft. In this 110
50 modification, the sleeve 24 is extended forwardly as at 70 to engage with a light spring 71 surrounding the inner end of the armature shaft. The stop washer in this modified form is shown at 72 bearing against a 115
55 conical shoulder 73 on the shaft and cooperating with the bearing 74 of the sleeve instead of with the end of the sleeve as in the previous forms. The main purpose of the structure of 120
60 this modified form is to adapt the invention to a standard type of armature shaft, the principles of structure and operation being substantially the same as in the other forms.

65 It will be noted that the transmission of power in each instance is from the electric

motor to the engine through a friction clutch while the actual engagement of the starter drive with the engine is by means of a gear and pinion. In a true sense there are no springs in the driving transmission, although a spring is used for increasing the friction of the clutch parts to the extent necessary to perform the work. This spring is substantially lax during the engaging operation except as previously pointed out, when end-butting of the teeth occurs. By reason of this construction, the shock of engaging impact is very greatly reduced. Full meshing of the pinion and ring gear must take place before the spring 30 can be sufficiently compressed to apply the necessary friction on the clutch parts to overcome the resistances of the engine. This compression is, of course, gradual and progressive and the force of rotative impact is applied so gradually as to reduce the shock to what is believed to be an absolute minimum in any electric motor starter which automatically engages with an engine gear upon the energization of the motor. 90

In prior starting devices damage to the teeth of engine ring gears and starter pinions results, more frequently perhaps, upon disengagement, than from jamming or butting in the engaging operation. This is due to the fact that the pinion is under definite torque control by the motor during the disengaging operation and at the instant of separation one set of teeth brushes the other with a definite force and definite opposition. It is to be particularly noted in the present case that the heavy spring becomes relaxed before the actual disengagement of the pinion teeth with those of the ring gear, leaving only the light spring effective on the friction clutch, which permits relative slippage of the clutch parts at the instant of disengagement. This neutralizes the motor torque or reduces its opposition so as to prevent any damage to the teeth of either part in the disengaging operation. 110

It has been found in the practice of the present invention that it is unnecessary to specially shape or point the teeth of the pinion although such special shaping or pointing may be adopted if desired. 115

What I claim is:—

1. A starting device for an internal combustion engine, comprising in combination, means adapted to move axially into and out of engagement with an engine part, an electric motor having means adapted upon energization of the motor to move the first said means axially into engagement with said engine part and transmit rotation thereto, the second said means comprising a slit connection, light resilient means preventing slip when the motor is originally energized, a heavy coil spring adapted to prevent slip during engagement and application of the normal load but designed to permit slip upon 130

backfire of the engine, said heavy resilient means becoming ineffective on the slip connection after the engine starts and before the first said means moves out of engagement with the engine part.

2. A starting device for an internal combustion engine, comprising in combination, a member adapted to mesh with and rotate an engine part, a driving shaft having threads, a friction cone clutch between the shaft and member and having a part engaging the driving shaft threads, a light compression spring arranged between the member and shaft, and adapted to have continuous but varying compression therebetween, a relatively heavy compression spring arranged normally substantially lax between the member and a portion of the clutch, said heavy spring being adapted to compress at the end of the meshing operation to substantially increase the degree of frictional engagement of the cone clutch parts.

3. A starting device for an internal combustion engine, having in combination, a driving shaft, an inner friction clutch member on said driving shaft means for moving said member axially upon rotation of said driving shaft, a sleeve surrounding said shaft, an outer friction clutch member axially movable in said sleeve but locked therewith rotatively, a pinion carried on said sleeve, a spring within the sleeve between a shoulder thereof and the outer friction clutch member, another spring between the sleeve and a shoulder on said driving shaft.

4. A starting device for an internal combustion engine, having in combination, electric motor means with threaded shaft rotated therefrom, a friction clutch member threaded on said shaft, a sleeve surrounding said shaft, a second friction clutch member in said sleeve, a spring between the shaft and the sleeve bearing at one end against the sleeve and the other end against the second said clutch member, a pinion on said sleeve, and yieldable means normally holding the clutch members in light frictional engagement.

5. A starting device for an internal combustion engine, having in combination, a motor with threaded armature shaft extension, a sleeve loosely mounted on said shaft extension, a friction clutch part threaded on said shaft extension, another friction clutch part splined in said sleeve, a heavy compression spring arranged normally substantially lax between a shoulder on the sleeve and the friction clutch part splined therein, and a relatively light compression spring bearing against the forward part of the sleeve and reacting against a shoulder on the shaft, and means movable with said sleeve to engage and rotate an engine part, said light spring being under partial compression when the sleeve is at the limit of its movement away from the engine part.

6. A starting device for an internal combustion engine comprising a driving shaft, a sleeve thereon having a pinion and a friction clutch member, a cooperative friction clutch member on the shaft, a coiled spring within the sleeve, means for advancing the pinion and the clutch members along the shaft to mesh the pinion with an engine gear, and respective stops for the pinion and one of the clutch members whereby the pinion is first stopped and the clutch member is later stopped after the spring has been compressed a predetermined amount.

7. A starting device for an internal combustion engine, comprising a driving shaft and a shaft to be driven, a pinion on the driving shaft, a friction clutch on the driving shaft, means for advancing the pinion and the clutch until the pinion connects with the shaft to be driven, a resilient means between the friction clutch and the pinion and means for causing a limited relative movement between a clutch part and the pinion after connecting the pinion with the driven shaft whereby the resilient means is compressed and impresses a definite friction on the clutch sufficient to turn the driven shaft under normal conditions but insufficient to hold under engine backfire conditions.

8. A starting device for an internal combustion engine, comprising in combination, an electric motor with extended armature shaft, a pinion adapted to engage an engine gear, friction clutch parts between the shaft and the pinion comprising a control member threadedly mounted on said shaft and adapted to move axially thereon when the motor is energized, a clutch unit intermediate said pinion and said control member including a normally lax compressible spring, stop means integral with said armature shaft adapted to contact directly with said control member whereby the compression of said spring is limited by the axial movement of said control member on the shaft.

9. An engine starting device comprising an armature shaft, a pinion thereon adapted to be moved into and out of mesh with an engine gear, a friction clutch between said shaft and said pinion, a spring surrounding said shaft, means operative by said shaft after meshing of the pinion with the engine gear for compressing the spring whereby the clutch friction is increased, and stop means acting directly upon said compressing means to limit the maximum friction obtainable in the clutch.

10. A starting device for an internal combustion engine, comprising a driving shaft, a pinion mounted for rotary and longitudinal movement relative thereto, a friction clutch interposed between said pinion and said shaft, a coiled spring surrounding said shaft, a control member for advancing the pinion along said shaft to mesh said pinion

- with an engine gear, said control member, after meshing of said pinion with said gear, compressing said spring to develop a progressively increasing torque in said friction 5 clutch, and respective stops for the pinion and the control member whereby the pinion is first stopped and the control member is later stopped after the spring has reached a predetermined degree of compression.
- 10 11. A starting device for an internal combustion engine, comprising a driving shaft, a pinion mounted for rotary and longitudinal movement relative thereto, a control member operatively connected to said shaft, a friction 15 clutch interposed between said pinion and said control member, a coiled spring surrounding said shaft, said control member, upon rotation of said shaft, advancing the pinion along said shaft to mesh said pinion 20 with an engine gear and compressing said spring to develop a progressively increasing torque in said clutch, and respective stops for the pinion and the control member whereby the pinion is first stopped and the control member is later stopped after the spring has 25 reached a determined degree of compression.
12. An engine starter drive comprising a power member, a transmission member mounted for rotary and longitudinal movement relative to said power member and connected to be driven thereby, an engine driving member connected to be moved by said transmission member into driving engagement with a member of the engine to be started, 30 a yielding torque transmitting drive between the transmission member and the engine driving member, means for progressively building up torque in the transmitting device, and means for limiting such building up to a pre- 35 determined value.
